UNITED STATES PATENT OFFICE.

STANLEY PONTIERE, OF OCEAN CITY, NEW JERSEY.

SUBMARINE LIFE-SAVING AND OBSERVATION TENDER.

1,019,356.

Specification of Letters Patent.

Patented Mar. 5, 1912.

Application filed December 6, 1910. Serial No. 595,925.

To all whom it may concern:

Be it known that I, STANLEY PONTIERE, a citizen of the United States, residing at Ocean City, in the county of Cape May and State of New Jersey, have invented certain new and useful Improvements in Submarine Life-Saving and Observation Tenders, of which the following is a specification.

This invention relates to submarine vessels and more particularly to means for egress and ingress thereto while submerged.

It has for an object the provision of a tender which may be carried within a submarine vessel, and means for releasing and returning the tender, and controlling its movement away from and toward the vessel.

A further important object is to provide means of communication between a person in the tender and those on the vessel, where- 20 by the tender may be used for making military and naval observations and the results reported currently to the submarine vessel while it remains unexposed and submerged at a safe distance.

25 Other objects and advantages will be apparent from the following description, and it will be understood that changes in the specific structure shown and described may be made within the scope of 30 the claims without departing from the spirit of the invention.

Additional advantages may also appear from the drawings, in which,

Figure 1, is a vertical sectional view of the 35 tender released and afloat, Fig. 2 is a fragmentary view of a submarine vessel and the well-dock for the tender.

Referring to the drawings, there is shown a portion of a submarine of any suitable 40 type, 10, located conveniently in which there is a well 11 of suitable size and shape communicating with the exterior of the vessel, preferably opening upward as shown, and arranged to be closed by a water proof clo- 45 sure 12, and provided with an access opening 13, communicating with the interior of the vessel for access of an operator to the well from the vessel. This opening is also arranged to be closed in a water-tight manner 50 by the door 14.

The well is adapted to receive through its exterior opening a tender 15, a buoy-like device circular in horizontal section, and approximately egg-shaped in vertical section, 55 though somewhat more elongated, its lower end portion being smaller than its upper.

The tender may be constructed of sheet metal or any other suitable material adapted to resist the pressure of water at the depths at which it is to be used. The upper end is 60 closed by means of a lid 16 hinged at one side to the body of the tender, and forming an observation dome, windows 17 closed in a suitable manner by glass of proper weight being provided in any number desired. 65 The lower rim of the lid is beveled at an angle of about 45 degrees to the major axis of the tender and provided with a gasket of rubber 18 or other suitable material arranged to seat snugly against a correspondingly beveled seat 19 formed around the upper edge of the body of the tender. At intervals around the lid-seat bifurcated lugs 20 are formed, and correspondingly spaced on the interior of the lid there are swiveled 70 bolts 21 arranged to swing into the lugs 20, to allow clamping of the lid securely in place by means of wing nuts 22 engaging against the lower sides of the lugs.

The tender is adapted to allow a man to 80 stand erect therein, a suitable floor 23 being hinged therein, and to allow an operator to sit at times a seat is provided, in two sections 24, hinged at opposite sides of the tender and arranged to abut at their outer 85 ends when swung into horizontal position, but being narrow enough to allow space at one side for the legs of the occupant. For communication with the parent vessel the tender is provided with telephonic apparatus 25, the connections for which will be subsequently described. For revivifying the air when it becomes foul through the breathing of an occupant, a tank of compressed oxygen may be detachably clamped 90 to the wall of the tender as at 26, and to allow escape of air as the oxygen is released, a suitable valve 27 is provided, that shown comprising simply a mushroom type seating exteriorly upon a properly ground seat 28, 100 its stem 29 extending slidably through a cage 30 between which and the valve a spring 31 is under tension to hold the valve seated to yield to proper pressure either by the compression of air in the major part of 105 the tender, or by the pressure of the occupant's finger upon the projecting portion of the stem.

The tender is controlled from the parent vessel by means of a suitable cable 35 suitably attached to the lower extremity of the tender and carrying suitable wires for form-

ing a circuit between instruments on the tender and others on the parent vessel. If found desirable a swivel connection for the cable may be provided, one method being illustrated. This includes the rotatable pin 36 engaged through a suitable stuffing box 37 in the tender bottom, and having the large eye 38 to which the cable 35 may be secured, and provided also with the axial 5 passage 40 through which wires may pass to the interior of the tender. Two telephone wires 39 are carried in a suitable manner by the cable 35, though they may be supported otherwise if found desirable. They are 10 passed through the passage 40, which is then closed in a suitable manner. The pin 36 is provided at its upper end with a retaining collar 41 recessed on its upper side and filled with insulating material having 15 in its upper surface two commutator rings 42, and the floor 23 carries suitable commutator brushes 43 from which lead wires 44 to the telephone 25.

For the control of the tender, the cable 35 20 is carried upon a reel 45, the hollow supporting shaft 46 of which extends through the walls of the well 11, and is provided with suitable operating mechanism, a simple crank 47 being formally shown. The 25 cable is suitably anchored to the reel, and the electrical wires carried thereby are carried into the shaft and connected to suitable commutator means 48 on the end of the shaft within the vessel, from which suitable 30 brush connections are made with wires 50 leading to the telephone 51 on the vessel. Suitable seat brackets 52 are provided within the well to support the tender above the cable reel.

Any suitable mechanism may be used for 35 operating the closure 12, and for removing and allowing ingress of water to the well. As shown, the closure 12 is provided with an upstanding arm 53, from which extends 40 a segmental rack 54, projecting into a correspondingly arcuate pipe 55, opening from the surface of the vessel and communicating with the well 11, both the segment and the pipe being concentric with the axis of the 45 hinge of the closure 12. The pipe 55 carries a suitable housing 56 within which a gear 57 is revolvably mounted, in mesh with the segment 54, and rotatable by means of the motor 58. A valve 59 is located inwardly of the housing 56, whereby the pipe 55 may be properly closed.

In operation, the closure 12 being closed and the well empty of water, a person desiring to leave the vessel opens the door 14, 50 lifts the lid 16 and enters the tender, closing both the door and lid. When in readiness he telephones to persons on board the vessel to operate the door lifting mechanism and water ingress valve, and when the closure 12 55 is completely open and the well full of

water, the tender rises by its own buoyancy to the surface, unreeling the cable 35 as it goes. The tender is designed to float with the joint between the lid and the body portion well out of water, as indicated in Fig. 1. 70

The tender is adapted well for use as a lift-saving means, by arranging the arm upon a pivot on the closure 12 so that the closure will be free to open without movement of the arm, and providing an emergency valve 60 adjacent the opening to the tender allowing slow ingress of water to the well. The escaping persons can then loosen the fastenings of the closure 12, and open the valve 60, having plenty of time 80 then to close the lid 16 and fasten it before the well is filled. The buoyancy of the tender when surrounded by water would then lift the closure 12, and allow its escape. It should be understood that in case of 85 emergency, if the tender must rise farther than the length of the cable before reaching the surface, the cable should be disconnected from the bottom of the tender.

Should it be desired to effect the return of 90 the tender to the vessel after release, the reel is operated to take up the cable, and it will be seen readily that from the shape of the tender it will readily guide itself into the well of the parent vessel. The closure operating mechanism is then operated to close the entrance to the well from the exterior, and the water therein pumped out through the pipe 62. Suitable means should be provided at 63 for admitting air to the well as 100 the water is removed. As soon as the water in the well has been lowered below the junction of the lid and the tender body, the person thereon may release himself by an operation the reverse of that described for 105 leaving the parent vessel.

What is claimed is:

1. In a device of the class described, a buoyant hollow body adapted for making visual observations, an anchorage member 110 revoluble in the bottom of the body and having portions disposed exteriorly and interiorly of the body, a cable member connected thereto, insulated electrical conductors extended through and insulated from the anchorage member, respective insulated 115 commutator rings carried by the inner portion of the anchorage member brush contact members engaged respectively with the rings, and electrical communication means within the body and in circuit with the contact members.

2. In a device of the class described, an observation tender comprising a hollow body having sights and means for supplying oxygen, a hollow pin engaged revolvably in the bottom of the body, an anchoring cable secured thereto, electrical conducting members extended inwardly through the pin 125 and insulated therefrom concentric insu- 130

- lated commutator rings carried by the pin within the body contact means engaged with the rings, and electrical devices within the body and in circuit with the contact means.
- 5 3. In devices of the class described, a parent body, a buoyant observation body separate therefrom, a revolute anchorage member extended through the bottom of the observation body, an anchoring cable secured thereto, and engaged with the parent body, electrical communication devices within each body, electrical conductors in circuit with the devices on the parent body and ex-

tended through the revolute member on the observation body, commutator rings carried by and insulated from the said revolute member contact means engaged therewith and connections between the contact means and the communication devices in the observation body. 15

In testimony whereof I affix my signature in presence of two witnesses. 20

STANLEY PONTIERE.
